UNITED STATES PATENT OFFICE.

HENRY D. BOKOP, OF DEFIANCE, OHIO.

COLLAPSIBLE SHIPPING-BOX.

1,373,162.

Specification of Letters Patent. Patented Mar. 29, 1921.

Application filed September 27, 1920. Serial No. 412,903.

To all whom it may concern:

Be it known that I, HENRY D. BOKOP, a citizen of the United States, residing at Defiance, in the county of Defiance and State 5 of Ohio, have invented a new and useful Collapsible Shipping-Box, of which the following is a specification.

This invention relates to collapsible shipping boxes or the like, and more particularly 10 to a novel means for securing a cover to the box, whereby the elements forming the securing means may be repeatedly employed for accomplishing the cover securing result.

The object of the invention is to provide 15 means cooperating with the securing wires of the box, whereby the securing wires may be bent to secure the cover to the box so that the ends of the wire will not break, during the bending operation.

20 With the foregoing and other objects in view which will appear as the description proceeds, the invention resides in the combination and arrangement of parts and in the details of construction hereinafter described and claimed, it being understood that 25 changes in the precise embodiment of the invention herein disclosed, may be made within the scope of what is claimed, without departing from the spirit of the invention.

30 Referring to the drawings:—

Figure 1 illustrates an end elevational view of a box constructed in accordance with the present invention.

Fig. 2 illustrates a plan view of one of 35 the securing plates.

Fig. 3 illustrates a side elevational view of a securing plate.

Fig. 4 illustrates a sectional view through one of the securing plates, at one end thereof, illustrating the manner in which the securing wires are connected thereto.

Fig. 5 illustrates a side elevational view of a shipping box; and

Fig. 6 illustrates a plan view of the same.

45 Referring to the drawings in detail, the box, which in the present instance is of a conventional design and includes the side walls 5 and 6 respectively, and bottom wall 7, there being provided a removable cover 8 for closing the open side of the box.

The securing plates 9 which are disposed in spaced relation with each other throughout the length of the box, form an important feature of the present invention, and each 55 of these plates includes a relatively long strip of material having spurs 10 stamped

from the body portion thereof, the spurs being disposed in staggered relation with each other, and spaced equidistantly apart, the spurs being designed to embed themselves in the cover so that the same will be secured against displacement thereon.

As shown, the ends of these plates indicated at 11 extend beyond the side walls of the box, as more clearly shown by Figs. 1 60 65 and 6 of the drawings, there being provided notched portions 12 formed in the side edges of the respective plates, the notched portions being of a contour to receive the securing wires indicated at 13, and which has 70 its extremities extending upwardly above the upper edges of the top of the box, the intermediate portions of the wires being secured to the sides and bottom of the box as 75 by means of the staples 14.

The wires 13 are arranged in such positions on the box that the upper ends thereof will lie in close proximity to the ends of the plates 9, so that the wires may be extended through the central opening 15 of the respective heads 11, where the same are passed over the upper surface of the heads and downwardly under the heads, the free ends of the respective wires being bent to overlie the heads, as indicated at 16, and more 80 85 clearly shown by Fig. 4 of the drawings.

From the foregoing it is obvious that due to the construction of the plates 9, the securing wires 13 may be secured to the ends thereof, in a manner to permit the wires to 90 be readily disconnected from the plates, all possibility of the wires becoming broken during the bending operation being eliminated, with the result that the wire may be repeatedly employed for securing the cover 95 to the box.

Having thus described the invention, what is claimed as new is:—

1. In a box construction, a removable cover, a plurality of securing plates having 100 spurs adapted to pass into the cover for securing the plates thereto, securing wires having connection with the box and having the ends thereof coiled around the ends of the plates, and said plates having their ends 105 terminating at points beyond the edges of the cover.

2. In a box construction, a removable cover, transversely extending plates secured to the cover in spaced relation with each 110 other, the ends of said plates extending beyond the side edges of the cover, the ends be-

ing provided with notched portions and a central opening, securing wires having connection with the box and having the ends thereof engaging within the notched portions, and said wires passing through the central openings.

5 In testimony that I claim the foregoing as

my own, I have hereto affixed my signature in the presence of two witnesses.

HENRY D. BOKOP.

Witnesses:

CLARA BOKOP BELL ,
J. L. MARKLEY.
